UNITED STATES PATENT OFFICE.

JOHN LIST, OF DETROIT, MICHIGAN.

SPACE-BAND CLEANER.

1,181,601.

Specification of Letters Patent.

Patented May 2, 1916.

Application filed October 10, 1913. Serial No. 794,383.

To all whom it may concern:

Be it known that I, JOHN LIST, a citizen of the United States, residing at Detroit, county of Wayne, State of Michigan, have 5 invented a certain new and useful Improvement in Space-Band Cleaners, and declare the following to be a full, clear, and exact description of the same, such as will enable others skilled in the art to which it pertains to make and use the same, reference being had to the accompanying drawings, which form a part of this specification.

This invention relates to space band cleaning devices and its object is a simple and 15 efficient machine for automatically cleaning space bands employed in linotype machines or the like.

During the casting of a line of type, the space bands become more or less leaded 20 after a short period of use, and it is necessary that these bands be kept perfectly clean to produce the most satisfactory result.

As a great number of space bands are used that continuously require being cleaned, 25 it is an object of the invention to provide a cleaning device that is not only automatic in action but that operates in a manner whereby each space band is rapidly and thoroughly cleaned and delivered in a stack 30 for ready removal from the machine.

These and other objects and novel features of construction are hereinafter more fully described and claimed and shown in the accompanying drawing in which--

35 Figure 1 is a side elevation of the device embodying my invention. Fig. 2 is a section on line $x-x$ of Fig. 1. Fig. 3 is a section on line $y-y$ of Fig. 1. Fig. 4 is an enlarged elevation partly in section of the 40 polishing rolls showing the race-way by means of which the bands are fed to the carriage. Fig. 5 is a detail of the brush for applying graphite to the polishing roll. Fig. 6 is a detail in perspective, showing a 45 portion of the carriage, the race-way for delivering the bands to the carriage, and the race-way for receiving the bands from the carriage. Fig. 7 is a detail of the friction clutch.

50 In the preferred form shown, 1 is a suitable frame or casing provided with a cover member 2. The cover member is formed with a chamber 3 in which a pair of polishing rolls 4 and 5 are positioned mounted on the shafts 6 and 7 respectively. In the recess behind the cover 2 the shafts 6 and 7 are provided

with intermeshing gears 8 and 9, and the shaft 6 extends through a bearing at the rear of the casing 1. Upon the outer end of the shaft 6 is loosely mounted a worm wheel 10 which is driven through the medium of the worm 11 on a shaft 12 of an electric motor 13, the frame 1 being preferably provided with an inclosing casing for the enumerated parts. Secured to the worm wheel 10 is a circular casing 80 within which is an expandible ring regulated by the hand wheel 81, the whole forming a friction clutch through the medium of which the worm wheel is secured to or loosened on the shaft. 60 The ring is secured to the shaft 6 and by turning the hand wheel 81 and expanding the ring to tightly engage the casing 80 the shaft 6 is made to turn through rotation of the worm wheel 10 by the motor. By such arrangement injury to the various parts is prevented in case the machine becomes accidentally stalled, as in such event, the casing 80 may revolve about the inclosed ring and the shaft 6 and the parts operated thereby 65 remain idle.

Mounted in bearings in the casing 1 is an idler gear 14 meshing with a gear 15 on the drive shaft 6. On the shaft of the idler gear 14 is a gear 16 meshing with a gear 17 70 on the shaft 18 mounted in bearings in the casing 1, which gears are all driven through the medium of the drive shaft 6, which by reason of its connection to the motor has the highest rate of speed, while the shaft 75 18 has the lowest rate of speed. The carriage 19 for the space band is U shaped as shown more fully in Figs. 2 and 6, being formed with two upwardly extending spaced members 20 and 21. The upper end of each 80 member 20 and 21 is provided with a lug 22 having a sharp undercut upper edge 23 to engage the side extensions 31 on the sliding portion 46 of the band as hereinafter 85 more fully described. At the rear edge the carriage is provided with a latterly extending flange portion 24 which rides in a slot 90 25 provided in the cover member 2 and is held therein by the retaining plates 28 forming a guideway for the reciprocation of the 95 carriage. To the lower end of the carriage 100 19 is secured a stub shaft 27 connected by a link 26 at the rear of the machine to the crank 29 on the shaft 18 as shown more clearly in Fig. 2. The rotation of the shaft 105 18, therefore reciprocates the carriage in the way 25.

Supported upon the front of the machine is an inclined raceway 30, in which the used space bands are placed in consecutive order, the projecting lugs 31 on the band ride on the way 32 provided upon each side of the raceway. Below the raceway 30 is a guide rod 90 which engages in the slot formed in the lower end of the space band. This guide rod prevents the bands from twisting in the raceway 30. In sliding down, the lowermost space band is picked up by the lugs 22 of the carriage and raised by its continued movement between the polishing rolls 4 and 5 on the shafts 6 and 7, the direction of rotation is shown by arrows in Fig. 4. The roller 5 is carried in a yoke 33 shown by dotted lines in Figs. 1 and 2, the lower end of which is pivoted to the shaft 18 and this yoke is held in position by a spring 34 so that the polishing roll 5 is pressed into engagement with the polishing roll 4, the purpose of which is to allow the roll 5 to draw away from the roll 4 as the wedge shaped space band is forced between the rolls. The spring 34 thus continuously holds the roll 4 in engagement with the band but the movement of the roll 5, and the shaft upon which it is mounted, is not so great as to draw the gears 8 and 9 out of mesh. The bearings for the shaft of the roll 5 are slotted to allow the roll to swing as described.

A receiving raceway 40 is pivoted at 41 to the frame by means of a stud 42, and about the stud is positioned a coiled spring 43 tending to hold the raceway with the forward end thereof against the upper portion 44 of the raceway 30, as is seen more clearly in Fig. 6. As the carriage 19 moves upward with a space band therein, the raceway 40 is raised by the upper end of the band, and, as the band passes upward with the carriage, the end of the raceway 40 drops into the slot 45 in the space band whereby, on the return of the carriage to its lowermost position, the upper sliding portion 46 of the band engages the raceway 40 and, as the carriage continues to descend it draws away from the band which is thus delivered onto the inclined raceway and down which it slides. The continuous operation of the carriage therefore, takes a band from the raceway 30, raises it between the polishing rolls and finally delivers it onto the receiving raceway 40. As the receiving raceway becomes filled, the operator may turn the raceway on its pivot and strip the cleaned space bands therefrom.

The polishing rolls may be of any approved type for the purpose, but are preferably of metal, which is grooved or scored on the face at an angle to the longitudinal axis. These grooves are preferably filled with graphite or other material suitable for the purpose. The bottom of the chamber 3,

in which the polishing rolls are situated, is formed in a manner to hold powdered graphite or other polishing powder, and the polishing rolls are continuously supplied with fresh powder by means of brushes 50, shown more clearly in Figs. 1, 4 and 5. The bristles forming the brush are mounted in a head 51, through which a rod 52 extends pivotally supported in the walls of the chamber 3. To the outer end of the rod 52 is an operating lever 53 extending downward below the bottom of the chamber and inwardly toward the cover plate 2, terminating in a curved portion 54 positioned in the path of movement of the portion 24 of the carriage 19. The normal position of these curved ends of the operating levers 53 is shown in Fig. 1, where they are seen to be practically in contact, and the bristles of the brush will then lie in the powder provided in the bottom of the case of chamber 3. Upon the upward movement of the carriage, the rounded upper end 55 of the portion 24 engages between the curved ends of the levers forcing them apart which rotates the brush head upon the pivots provided and brings the powder covered bristles in contact with the polishing rolls and thus supplies fresh powder thereto. As the carriage descends the brushes fall back into the powder by reason of the action of the coil springs 56 tending to hold the brushes out of contact with the polishing rolls. At each operation of the carriage the rolls are thus supplied with fresh powder.

During the polishing operation considerable polishing powder will fall through the opening in the bottom of the chamber through which the carriage and space band reciprocates and, to prevent waste I preferably provide a receptacle 60 near the base of the machine to receive the powder which may be again placed in the chamber 3 through an opening provided in the top thereof.

From the foregoing description it becomes evident that the device is of simple and compact construction and is automatic in operation, it simply being necessary to supply the raceway 30 with the used bands and to remove the cleaned bands from the raceway 40. The band is carried to and from the polishing rolls by the carriage and is thus guided in its movement.

Having thus briefly described my invention, what I claim and desire to secure by Letters Patent of the United States is—

1. In apparatus of the kind described, a polishing device, a raceway for holding a plurality of space bands, a reciprocable holder or carriage adapted to consecutively remove the bands from the raceway and submit each to a polishing operation by the polishing device, means for positively reciprocating the carriage, and automatic means

for removing the polished bands from the holder.

2. In apparatus of the character described, a polishing element, a raceway adapted to support a plurality of space bands, a reciprocable carriage adapted to consecutively remove the bands from the raceway and submit each to operation by the polishing element, means for driving the polishing element, a shaft provided with a crank, a link connecting the crank and carriage, a gear train whereby the driving means may rotate the shaft and reciprocate the carriage, and automatic means for removing the polished band from the carriage.
3. In apparatus of the character described, a pair of polishing rolls geared together to rotate in reverse directions, one of said rolls being fixed in position and the other of said rolls being yieldably held in contact therewith, a raceway adapted to support a plurality of space bands, a carriage adapted to successively remove bands from the raceway and submit each to operation by the polishing rolls, a shaft having a crank, a link connecting the crank and the carriage, a gear train between the said shaft and the fixed polishing roll whereby rotation thereof rotates the said shaft, and automatic means for removing the polished band from the carriage.
4. In a device of the kind described, a pair of polishing rolls, one of said rolls being fixed in position and the other of said rolls being yieldably held in contact therewith, means for driving the fixed roll, an inclined raceway adapted to support a plurality of space bands down which they are fed by gravity, a carriage adapted to successively remove a single band from the raceway and move it to and between the polishing rolls and thereafter deliver the band to a receiving holder, means whereby the carriage has a slow movement throughout its reciprocation in comparison with the speed of movement of the polishing rolls, and means interposed between the carriage and the fixed roll for operating the carriage.
5. In a device of the kind described, a fixedly positioned polishing roll, a pivotally supported, spring pressed, polishing roll, an inclined raceway adapted to support a plurality of space bands down which they are fed by gravity, a reciprocable carriage adapted to successively receive a single band from the raceway and move it to and between the polishing rolls and thereafter deliver the cleaned band to a receiving holder, means whereby the carriage has a slow movement throughout its reciprocation in comparison with the speed of movement of the polishing rolls, and means for rotating the rolls at a high rate of speed and simultaneously comparatively slowly, move the carriage.
6. In a device of the kind described, a pair of polishing rolls, yieldable means tending to hold the rolls in contact, an inclined raceway for supporting a plurality of space bands at their upper ends and down which they are fed by gravity, a guide bar for the lower ends of the bands, a reciprocable carriage adapted to successively remove a single band from the raceway and move it between the polishing rolls, a spring pressed receiving holder adapted to normally engage against the end of the inclined raceway in the path of movement of the space band, whereby upon the withdrawal of the band from between the rolls it is deposited on the receiving holder.
7. In a device of the kind described, a framework, a chamber therein, a pair of polishing rolls mounted in said chamber and yieldably held in contact, the bottom of said chamber being adapted to hold polishing powder, brushes pivotally mounted in the framework and normally lying in the powder space, a holder for supporting a plurality of space bands, a reciprocable carriage adapted to successively remove a single band from the raceway and insert it between and withdraw it from the polishing rolls, said pivotally mounted brushes being provided with operating levers projecting into the path of movement of the carriage whereby said brushes are alternately brought into engagement with the faces of the polishing rolls and returned into the powder holding space, and automatic means for removing the cleaned band from the carriage during the withdrawing movement thereof.
8. In apparatus of the character described, a pair of polishing rolls, intermeshing gears on said rolls, one of said rolls being fixedly positioned and the other of said rolls being yieldably held in contact therewith, means for driving the fixedly positioned roll, a raceway adapted to support a plurality of space bands, a reciprocable carriage adapted to successively remove the bands from the raceway and submit each to a polishing operation by the rolls, a guideway for the carriage, a shaft having a crank, a link connecting the crank with the lower end of the carriage, a gear on the said shaft, and a gear train providing a driving connection between the said gear on the shaft and the fixed polishing roll of such nature that the roll may have a high speed of revolution while the carriage may move slowly.
9. In apparatus of the character described, a pair of polishing rolls in geared relation for rotation in reverse directions, one of said rolls being fixed in position and the other of said rolls being yieldably held in contact therewith, driving means, an adjustable friction drive through operation of which the driving means may rotate the

fixedly positioned roll, a raceway adapted to support a plurality of space bands, a carriage adapted to consecutively remove bands from the raceway and submit each to operation by the polishing rolls, means for moving the carriage slowly in comparison to the speed of movement of the polishing rolls during the entire time of engagement of the space-band with the rolls, and automatic

means for removing the polished band from the carriage.

In testimony whereof, I sign this specification in the presence of two witnesses.

JOHN LIST.
